ASH TRAY

Robert W. Giles, Sr., Mountain Home, Tenn.

Application February 2, 1950, Serial No. 7,683

Term of patent 14 years

(Cl. D85—2)

To all whom it may concern:

Be it known that I, Robert W. Giles, Sr., a citizen of the United States of America, residing at Mountain Home, in the county of Washington, State of Tennessee, have invented a new, original, and ornamental Design for an Ash Tray, of which the following is a specification, reference being had to the accompanying drawing, forming a part thereof.

Fig. 1 is a perspective view of an ash tray showing my new design.

Fig. 2 is a top plan view of Fig. 1.

The characteristic feature of the design resides in the centerpiece.

I claim:

The ornamental design for an ash tray, substantially as shown and described.

ROBERT W. GILES, SR.
